UNITED STATES PATENT OFFICE.

LEWIS A. PRIESS, OF MINNEAPOLIS, MINNESOTA.

EASY-SLIDE HOLDER FOR NECKTIES.

1,095,736.

Specification of Letters Patent.

Patented May 5, 1914.

Application filed December 11, 1911. Serial No. 665,200.

To all whom it may concern:

Be it known that I, LEWIS A. PRIESS, a citizen of the United States, residing at Minneapolis, in the county of Hennepin and State of Minnesota, have invented certain new and useful Improvements in Easy-Slide Holders for Neckties, of which the following is a specification.

My invention relates to a device to be applied to the band of a necktie and inserted within the fold of the collar, providing an easy slide holder for neckties.

It is the object of my invention to provide a device as above described which shall be cheap, easily applied to the necktie, and in connection with the necktie be applicable to the inside of the folded collar with greater ease than would be the case with the necktie alone, and which after being placed in position will hold the necktie so as to permit the same to slide easily back and forth for adjusting the knot in the tie after the same has been formed.

In the drawings, illustrating the application of my invention in one form,—Figure 1 is a plan of my device and Fig. 2 a sectional view taken through the device when containing a necktie and placed within a turned-down collar.

The body 10 of the holder comprising my invention will be formed of celluloid, rubber composition, light metal, or other substance having a smooth and glossy surface which at the same time is light, resilient and of sufficient tenacity not readily to collapse or squeeze together. The body portion 10 has formed along the edges thereof a series of lobes 11 which are turned inwardly and spaced from the body portion, as clearly shown in Fig. 2. The body portion will be provided with a notch for the reception of the collar button, as shown in Fig. 2, the body portion having a slightly raised part 14 in which the small notch 12 is provided

to receive the collar button 13. The advantage of the structure shown in Fig. 1 is that the collar button is, by the means therein shown, removed from contact with the tie 16. The notch 12 engages the shank of the collar button 13 when the holder is placed in position in the collar. The holder is of sufficient length to extend around the curved portions of the collar at either side so that the ends of the holder will be directed to-

ward the front of the collar. The lobes 11 will engage the front wall of the collar and hold the same away from the band of the tie 16 held between the body 10 and the lobes 11. Owing to the fact that the surface of the holder is smooth and glossy the tie will be capable of slipping readily within said holder. The engagement of the collar button with notch 12 will prevent the holder from slipping while at the same time, it will not contact with the tie or operate in any way to bind or hold it from readily sliding within the holder and collar. The advantages of such a device will be apparent. It can be manufactured very cheaply, so that such a holder may with economy be applied to every tie in a person's wardrobe and thus be at all times available for use irrespective of the tie which may be selected at any time. The holder may be inserted in and withdrawn from the collar in conjunction with the tie with the utmost ease.

It will be noted that my tie holder not only provides means for holding the tie so it will not be squeezed by the bands of the collar, and therefore so it can readily be caused to slide in positioning the same, but the holder also prevents the tie from slipping down, holding it up in the upper part of the collar band where the knot will always be properly positioned. It will operate so to hold the tie regardless of the extent to which the same may be slid back and forth in positioning the knot, since the notch in the holder engaging the collar button above the shank thereof will not only hold the holder from movement longitudinally in the collar button, but also will hold it from slipping down, and, of course, the lobes on the holder engaging the band of the tie will prevent the tie from moving away from the holder, so that the tie will be held up in proper position without possibility of slipping down.

I claim:

A necktie holder comprising a body portion formed of a thin strip of celluloid or the like and provided along the edges thereof with a plurality of inturned lobes for embracing the tie and holding the same out of contact with the flaps of the collar when said holder and tie are positioned between said flaps, the said body portion having formed on one edge thereof an offsetting strip pro-

vided with a notch for receiving the shank of the collar button, said notch being entirely outside of the line of the inside engaging portions of said lobes so that when 5 the collar button is seated in the notch the tie can not contact with the collar button to be caught and restrained thereby.

In testimony whereof I affix my signature in presence of two witnesses.

LEWIS A. PRIESS.
